UNITED STATES PATENT OFFICE.

LEE S. BURRIDGE, DECEASED, LATE OF NEW YORK, N. Y., BY FRANCIS O. BURRIDGE, EXECUTOR, OF NEW YORK, N. Y., ASSIGNOR, BY MESNE ASSIGNMENTS, TO UNDERWOOD TYPEWRITER COMPANY, OF NEW YORK, N. Y., A CORPORATION OF DELAWARE.

TYPE-WRITING MACHINE.

1,317,482.

Specification of Letters Patent. Patented Sept. 30, 1919.

Original application filed September 27, 1915, Serial No. 52,594. Divided and this application filed November 10, 1917. Serial No. 201,260.

To all whom it may concern:

Be it known that LEE S. BURRIDGE, deceased, late a citizen of the United States, and late residing in the borough of Manhattan, county, city, and State of New York, invented certain new and useful Improvements in Type-Writing Machines, of which the following is a specification.

This invention relates to carriage-controlling mechanism for typewriting machines.

This application is a division of pending application No. 52,594, filed September 27, 1915.

An object of this invention is to provide a simple and efficient escapement mechanism which may be economically manufactured and easily assembled.

In the type of machine illustrated, the platen carriage is mounted upon a frame which is shiftable up and down to various positions for permitting the printing of different case types. This shiftable frame comprises front and back sheet-metal plates. The escapement wheel is mounted between these front and rear plates. The loose dog and the fixed dog of the escapement mechanism are carried by a rocking plate which is journaled between said front and rear plates. This dog rocker may be made of sheet-metal, and supported upon a sheet-metal bracket secured to one of the transverse plates of the shifting frame. A universal bar located beneath the keys of the machine is provided with a connection to the dog rocker. The dog rocker is provided with a slot, the sides of which are engaged by the connections from the universal bar. This slot is elongated so that the dog rocker will always be under the control of the universal bar in all case-positions of the shifting frame upon which the dog rocker is mounted.

The dog rocker is mounted upon a vertical axis for a horizontal movement, and the shifting frame is mounted for a substantially vertical movement, and a slot in the dog rocker is vertically disposed so that the leverage between the dog rocker and the connections from the universal bar remain constant, irrespective of the different vertical positions occupied by the dog rocker.

The loose dog, in the present invention,

is normally in engagement with the escapement wheel. When the universal bar is operated the loose dog is withdrawn from the escapement wheel and permitted to move under the influence of a spring, into a position in which it will be engaged by the next succeeding tooth when returned to the escapement wheel. For limiting the loose dog in this movement the present invention provides a spring instead of a fixed stop, as has heretofore been done. With this arrangement when the carriage is moved in anti-letter-feed direction, and the escapement wheel which is connected thereto by the pinion and rack is rotated, the limiting spring will yield and permit the teeth of the escapement wheel to cam said dog to abnormal position to permit the teeth to pass the dog. This obviates the necessity of providing a one-way connection between the escapement wheel and the carriage in order to permit the carriage to be returned or set back.

To aid in assembling the parts and to permit the removal of the rack and escapement wheel, for the purpose of changing the extent of the letter-space movements which the typewriter carriage receives from the escapement mechanism, the carriage rack and the escapement wheel are both mounted so as to be readily removed. For this purpose the escapement wheel is mounted on a rod or shaft, bearing in the front and rear shift frame plates, which may be entirely withdrawn from its supports. This withdrawal of the shaft permits the removal of the escapement wheel. The shaft is positively held in the machine against turning and withdrawal by means of an arm, secured to the shaft, which may be held to the frame by means of a screw. The carriage rack is journaled on trunnions, one of which extends into a socket in the carriage frame, and the other of which extends into a socket in a bracket which is removably held to the carriage frame by a pair of screws.

Other features and advantages will hereinafter appear.

In the accompanying drawings,

Figure 1 is a side elevation, showing the shiftable platen frame.

Fig. 2 is a rear elevation, showing part of the spring-drum mechanism.

Fig. 3 is a detail sectional view of the carriage spring mechanism.

Fig. 4 is a rear sectional view, showing part of the escapement mechanism.

5 Fig. 5 is a sectional elevation, showing the mounting of the escapement wheel.

Fig. 6 is a side elevation, showing the connections from the keys of the machine to the escapement mechanism.

10 Fig. 7 is a sectional top-plan view, showing the parts shown in Fig. 4.

Fig. 8 is a front elevation, showing the carriage rack and escapement mechanism.

Type-bars 10 are swung upwardly and 15 rearwardly against the front face of a platen 11 at the depression of keys 12 mounted on key levers 13. The platen 11 is mounted on an axle 14 rotatably mounted in side plates 15 forming part of a typewriter carriage 16; said typewriter carriage also comprising bars 17 serving as rails for ball-bearings 18, upon which the carriage rides in letter-feed and return directions. The ball-bearings are confined between the 20 rails 17 and forward and rearward plates 19 and 20 which form part of a frame 21. The frame 21, which also comprises side plates 22, is suitably guided and shiftable substantially vertically, for the purpose of 25 moving the platen to various case-printing positions.

The typewriter carriage normally tends to move in letter-feed direction under the influence of a spring 23 connected by a cord 35 or tape 24 to the carriage 16.

The letter-feed movement of the typewriter carriage is controlled by an escapement mechanism, which comprises an escapement wheel 25 and also a pinion 26 engaging 40 a rack 27 carried by the typewriter carriage. The escapement wheel 25, formed with a hub 28 to which the pinion 26 is secured, is mounted to rotate on a pin 29 which passes through the hub 28, and which is mounted 45 in the forward and rearward plates 19 and 20. The pin 29 is mounted at one end in a bushing 30 secured to the front plate 19, which is of sheet-metal, and at its other end in a bushing 31 secured to the rear plate 20, 50 which is also of sheet-metal. The bushing 31 extends from the rear plate 20 forwardly and acts as a spacer for holding the escapement wheel against lateral movement on the pin 29; the escapement wheel being confined between the bushing 31 and the bushing 30. So that the parts may be conveniently assembled and removed from the machine, the pin 29 is removably held in the machine by a plate 32 riveted to one 60 end of the pin 29. The plate 32 is secured to the rear plate 20 by means of a screw 33.

The escapement wheel 25 is normally prevented from rotating under the influence of the carriage spring 23, by an escapement 65 dog 34 which engages with one of the teeth

35 of the escapement wheel. The dog 34 is pivotally mounted at 36 upon a plate 37, and is limited in its movement in one direction by means of a stop-pin 38 secured to the plate 37. The carriage spring 23 70 through the rack 27 and the pinion 26 normally tends to rotate the escapement wheel, and, therefore, the escapement dog 34 is normally held against the stop-pin 38. The plate 37, which is preferably stamped from 75 sheet-metal, is mounted for a horizontal rocking movement on trunnions 39 riveted to ears 40, formed integral with the plate 37, and having headed ends extending through ears 41 on a bracket 42 secured to the rear 80 plate 20.

When the rocker plate 37 is moved by mechanism hereinafter described, the loose dog 34 is moved out of engagement with the tooth 35 on the escapement wheel, and a 85 fixed dog 43 formed integral with the plate 37 is moved into engagement with the escapement wheel, to hold the same temporarily against movement. Thus freed from the escapement wheel the loose dog 34 is 90 moved up by a draw-spring 44, connected to an arm 45 extending from said dog, into the position shown in Fig. 4, in dot-and-dash lines. In this position the dog 34 is 95 located opposite the next tooth on the escapement wheel, so that when the rocker plate is returned to normal position by its spring 46, (see Figs. 6 and 7), and the fixed dog 43 is moved out of engagement with the escapement wheel, the loose dog 100 105 will be moved into position to engage the said next tooth on the escapement wheel. After the escapement wheel has been released by the fixed dog 43, the carriage feeds and the escapement wheel, under the carriage spring influence, rotates until the 110 said next tooth 35 strikes the dog 34 and moves the same against the tension of its spring 44 until the lower edge of the dog is arrested by the stop 38 on the rocker plate 115 37, which causes the carriage to also be arrested.

The loose dog 34 is usually limited in its upward movement to the dot-and-dash line position, shown in Fig. 4, so as not to move 115 out of reach of the escapement wheel, by a fixed stop, but in the present invention said dog is limited by a draw-spring 47. This spring 47, with the spring 42, normally tends to move the dog to the dot-and-dash line 120 position, shown in Fig. 4, and no farther. The omission of the customary stop is advantageous in that the noise accompanying the operation of the machine is reduced. Spring 47 returns the dog to the midway 125 (dot-and-dash) position after said dog has been vibrated upwardly beyond the dot-and-dash position by the reversely moving escapement wheel as the carriage is drawn back. Springs 44 and 47 diverge from the 130

dog arm, so that by vibrating said dog either spring may be made effective as the other is simultaneously made comparatively ineffective. For example, at Fig. 4, spring 44 is effective while 47 is substantially ineffective, being on the "dead center".

Another advantage of this arrangement is that when the carriage is moved in anti-letter-feed direction, the loose dog 34 may 10 be moved up against the tension of the spring 47 by the escapement wheel to an abnormal position, until the teeth of the escapement wheel may pass the dog. If the loose dog 34 was limited in its upward movement, to its position to engage the next tooth of the escapement wheel, after said wheel is released by the fixed dog, then said fixed stop would operate to prevent the backward rotation of the escapement wheel, and 15 therefore the anti-letter-feed of the platen. The present invention, therefore, simplifies and reduces the cost of the device by obviating the necessity of providing a one-way connection between the escapement wheel 20 and the carriage, which has heretofore been the practice, in order to permit the carriage to be moved in anti-letter-feed direction.

The mechanism for operating the rocker plate 37 from the keyboard of the machine 30 to cause the letter-feed movements of the carriage will now be described.

A universal bar 49, extending across the machine and located directly beneath the key levers 13, is pivoted at its rear end in 35 brackets 50, which, in turn, are secured to a transverse bar 51 of the main frame. Each of the key levers 13 has a shoulder 52, adapted, when the key lever is depressed, to strike and depress the universal bar. The 40 universal bar is connected to rock the dog plate 37 by means of a rock shaft 53, which has arms 55 connected by links 56 to the universal bar 49. The rock shaft 53 is journaled in brackets 54 which are secured to 45 the bar 51. A link 56 in an arm 55 is provided for each side of the universal bar. The rock shaft 53, the arms 55 and the links 56 connect the opposite sides of the universal bar, and therefore cause said universal bar to descend uniformly whether 50 operated by a key at one side of the machine or the other. The rock shaft 53 has an arm 57 secured thereto, which at its upper end is connected to a draw bar or link 58. The 55 draw bar 58 is connected at its forward position to the arm 57 by a pin 59 secured to the draw bar, and at its rearward portion to a supporting lever 60. Secured to the rearward portion of the draw bar 58, 60 which is preferably of sheet-metal, is a threaded post or pin 61, which extends through an opening 62 in the end 63 of the rocker plate 37, and has a head or nut 64 thereon which engages with the sides of the 65 opening 62. The nut 64 is adjustably held

against movement on the threaded pin 61 by means of a lock nut 65.

The opening 62 is elongated so that the rocker may rise with the shift frame to the various case-positions, without permitting 70 the pin 61 and nut 64 of the draw bar to become disengaged from the dog rocker; therefore, the universal bar may operate the dog rocker in all case-positions of the shift frame. The slot 62 is arranged to substantially parallel the axis about which the dog rocker pivots. In the present case the dog rocker axis is vertically disposed, and, therefore, the slot 62 is vertically disposed. This arrangement permits the shifting of the dog 75 rocker with respect to the draw bar without varying the leverage or altering the amount of movement which the dog rocker will receive from the universal bar. The portion 80 63 of the dog rocker is tilted slightly, so as to parallel the path of movement of the shift frame to further aid in maintaining the connections between the universal bar and the dog rocker constant. The slot 62 has an open end 62a so as to permit the device 85 to be easily assembled. Said axis of the dog-rocker pivot extends about in the direction of case-shifting movement of the platen, whereby the key connection is able to have the same control of the rocker in all 90 case-shift positions.

When a key lever 13 is depressed by its key 12, the shoulder 52 on said key lever operates the universal bar 49, and in doing so, rocks the shaft 53 through the links 56 100 and the arms 55, to move the draw bar 58 forwardly so that said draw bar 58 will rock the dog plate 37 to move the loose dog 34 out of engagement with the escapement wheel. As the key rises under the influence 105 of its spring 66, the dog rocker 37, through its spring 46, returns the draw bar 58 and the lever 60, on which it is floatedly mounted, to normal position; at the same time as the loose dog 34 is being moved into co-operative position with the next tooth on the escapement wheel, the dog rocker and draw bar and the lever, on which the draw bar is mounted, are limited in this return movement by a stop 67 (see Fig. 7), formed 110 on an arm 68 secured to the rear plate 20. The connection 61, 64 is universal to the keys.

In order that the rock shaft 53, which is operated by the universal bar, may perform 120 other functions before the escapement mechanism is operated, and in order that the escapement mechanism may be operated only at the end of the key-stroke, the draw bar 58 is slotted at 69, so that the pin 59 in the 125 arm 57 may have a limited lost-motion before operating said draw bar. A spring 70, secured at one end to the draw bar 58 and at the other end to the arm 57, holds said arm and therefore the universal bar 49 in 130

normal position. The spring 70 is weaker than the spring 46, which holds the dog rocker 37 and the draw bar 58 in normal position. Therefore, in the first part of 5 the movement of the arm 57, as the key is depressed, the spring 70 yields and the draw bar is not moved until the pin 59 on said arm 57 reaches the end of the slot 69 in the draw bar.

10 So that the universal bar will cause the feed of the platen in all case-positions of the latter, the opening 62 in the dog rocker 37, through which the draw bar 58 passes, is elongated so that the draw bar, which is 15 mounted in the main frame, will always remain in operative engagement with the dog rocker 37, which is mounted in the main frame 21, which, in turn, has a substantially vertical shifting movement relative to the 20 main frame.

A space-key 71 is carried by a lever 72 fast on a rock shaft 73 to which is also fastened an arm 74 which is connected by a link 75 to operate the lever 60, on which the draw bar 25 58 is floatedly mounted. The space-key and associated parts are held in normal position by a spring 76 connected to the arm 74 and at the other end to the frame of the machine. When the space-key 71 is depressed, the arm 30 74 and the link 75 are moved forward. This moves the draw bar forward, so that the nut 64, carried by said draw bar, engages with the portion 63 of the dog rocker and operates the escapement mechanism. So that the 35 space-key which is connected to the draw bar will not be operated when the draw bar is operated through the universal bar 49, the lever 60 is slotted at 77. This slot permits the lever 60 to be moved forward without 40 operating the link 75, but permits the link 75, when moved forward, to operate the lever.

The carriage rack 27 is pivotally mounted on the typewriter carriage, and has secured thereto a handle or finger-piece 79, so that when the operator desires to move the typewriter carriage in letter-feed direction without interference from the escapement mechanism, the carriage rack may be released 45 from the escapement wheel by operating said finger-piece to move the rack 27 out of engagement with the pinion 26 secured to the escapement wheel. The finger-piece 79 is located in a place where it is convenient 50 to the operator. The rack 27 is limited in its swinging movement in one direction by means of a stop 80 riveted to the rear carriage rail 17.

In order to facilitate the assembling and 60 dis-assembling of the rack 27, said rack is mounted at one side on a trunnion 81, formed on said rack, which extends into an opening 82 in the side plate 15 of the typewriter carriage, and at the other side on a 65 trunnion 83, also formed on said rack, which

extends into a hole 84 in a bracket 85 secured to the other side plate 15 by screws 86.

With this arrangement the rack may be attached to the carriage after the side plates 15 and the rails 17 have been riveted together. In attaching the device the trunnion 81 is first slipped in the opening 82, then the bracket 85 is slipped on the trunnion 83, and then the bracket 85 is secured to the side plate 15 by the screws 86. If it is 75 desired at any time to remove the rack 27 for the purpose of repair, or for substituting a rack of different pitch, the screws 86 are withdrawn, after which the rack may be readily slipped out of its bearing in the side 80 plate 15. It will be seen that the escapement wheel 25 and the pinion 26 may also be readily removed from the machine for the purpose of making repairs or substituting a pinion and escapement wheel of different pitch. To remove the escapement wheel and pinion, it is only necessary to withdraw the screw 33 and then pull the pin 29 with its plate 32 out of its supports. This would permit the escapement wheel to be 90 slipped out of its position in the frame.

The removable rack and removable escapement wheel and pinion make it extremely convenient to change the machine from one size letter-spacing to another; 95 and it will be seen that this change may be accomplished without dis-assembling the machine to any great extent.

Variations may be resorted to within the scope of the invention, and portions of the 100 improvements may be used without others.

Having thus described the invention, what is claimed is:

1. In a typewriting machine, the combination with a platen, of means for driving the 105 platen in letter-feed direction, and an escapement mechanism for controlling the driving of the platen comprising a toothed wheel, a pair of dogs for holding said wheel, a rocker plate for supporting said dogs, 110 means for vibrating said rocker plate to move said dogs into and out of the plane of the wheel, and two draw-springs attached to an arm provided upon one of said dogs, one for rocking the dog toward a succeeding tooth on the wheel, when it has been disengaged from one tooth of the wheel by movement of the rocker plate, and the other spring for returning the dog after it has 115 been displaced by the reverse rotation of the wheel; said springs diverging from said dog arm in a manner that the operation of said dog may render either spring effective and the other simultaneously ineffective.

2. In a typewriting machine, the combination with a platen, of a carriage for said platen, a frame for said carriage comprising front and rear sheet-metal plates, an escapement wheel mounted between said front and rear plates, and a rod on which said escape- 125 130

ment wheel is mounted, said rod being mounted in bosses secured to said plates.

3. In a typewriting machine, the combination with a platen, of a carriage for said platen, a frame for said carriage comprising front and rear sheet-metal plates, an escapement wheel mounted between said front and rear plates, and a rod on which said escapement wheel is mounted, said rod being removably mounted in bosses secured to said plates, said rod being held in position in the plates by an arm to which it is secured, and said arm being removably secured to one of said plates.

15 4. In a typewriting machine, a main frame, a platen frame shiftable between case-positions on the main frame, a platen mounted for letter-feed movement on the platen frame, means for driving the platen in letter-feed direction, an escapement mechanism in the platen frame for controlling the letter-feed drive of the platen, type keys on the main frame, and a universal connection from said keys to the escapement mechanism for operating the latter; said escapement mechanism comprising a toothed wheel, a dog adapted to be rocked into and out of engagement with said wheel, and a carrier for said dog having therein a slot through which the carrier is engaged and rocked by the connection from the type keys, said slot permitting shift of the carrier with the platen frame without shift of the type-key connection.

35 5. In a typewriting machine, a main frame, a platen frame shiftable between case-positions on the main frame, a platen mounted for letter-feed movement on the platen frame, means for driving the platen in letter-feed direction, an escapement mechanism on the platen frame for controlling the letter-feed drive of the platen, type keys on the main frame, and connections from said keys to the escapement mechanism for operating the latter; said escapement mechanism comprising a slotted rocker with which the type-key connection is in slidable engagement, so that the rocker may be shifted with the platen without shift of said key connection, the axis of rocking movement of said rocker extending about in the direction of the case-shifting movement of the platen.

6. In a typewriting machine, a main frame, a platen frame shiftable between case-positions on the main frame, a platen mounted for letter-feed movement on the platen frame, means for driving the platen in letter-feed direction, an escapement mechanism on the platen frame for controlling the letter-feed drive of the platen, a space-key on the main frame, and connections from said key to the escapement mechanism for operating the latter; said escapement mechanism comprising a toothed wheel, a dog adapted to be rocked into and out of en-

gagement with said wheel, and a carrier for said dog having therein a slot through which the carrier is engaged and rocked by the connection from the space-key, said slot permitting shift of the carrier with the platen frame without shift of the key connection.

7. In a typewriting machine, a main frame, a platen frame shiftable between case-positions on the main frame, a platen mounted for letter-feed movement on the platen frame, means on the platen frame for driving the platen in letter-feed direction, type keys, and mechanism actuated thereby for controlling the letter-feed drive of the platen, said key-actuated mechanism comprising a universal bar on the main frame, an arm connected to the bar to be rocked thereby, a link vibrated by said arm, and a rocker on the platen frame vibrated by said link, said rocker having a vertical slot engaged by said link to accommodate the case-shift movements of the rocker, and the axis of rocking movement of the latter extending about in the direction of the case-shift movement.

8. In a typewriting machine, a main frame, a platen frame shiftable between case-positions on the main frame, a platen mounted for letter-feed movement on the platen frame, means on the platen frame for driving the platen in letter-feed direction, type keys, and mechanism actuated thereby for controlling the letter-feed drive of the platen, said key-actuated mechanism comprising a universal bar on the main frame, a rod on the main frame extending forward and rearward thereon, a connection from the universal bar to the rod for reciprocating the same, and a rocker on the platen frame having a vertical slot engaged by the rod, to enable the rod to actuate the rocker at all case-shift positions of the rocker.

9. In a typewriting machine, a main frame, a platen frame shiftable between case-positions on the main frame, a platen, means for driving the platen in letter-feed direction on the platen frame, and an escapement for controlling the drive of the platen, comprising a toothed wheel, a dog-carrying rocker shiftable with said platen frame, and an actuator for the rocker in engagement therewith, said rocker having a vertical slot engaging said actuator to permit shift of the platen frame with respect to the actuator, and the axis of rocking movement of the rocker extending about in the direction of its case-shift movement.

10. In a typewriting machine, a main frame, a platen frame shiftable between case-positions on the main frame, a platen, means for driving the platen in letter-feed direction on the platen frame, and an escapement for controlling the drive of the platen, comprising a toothed wheel, a dog-carrying rocker shiftable with said platen frame, and

an actuator for the rocker in engagement therewith, said rocker having a vertical slot engaging said actuator to permit shift of the platen frame with respect to the actuator, 5 and the axis of rocking movement of the rocker extending about in the direction of its case-shift movement; said rocker having the part thereof engaged by the actuator inclined in the direction of shift of the platen 10 frame, so that the movement of the rocker and actuator may be the same in all case-positions of the platen frame.

11. In a typewriting machine, a main frame, a platen frame shiftable between case-positions on the main frame, a platen mounted for letter-feed movement on the platen frame, an escapement on the platen frame for controlling the letter-feed movement of the platen, type keys, a universal bar, a 20 space-key, a connection for operating the escapement from the universal bar, a connection for operating the escapement from the space-key independently of the operation of the universal bar, and means for shifting the 25 platen frame without breaking said escapement-operating connections.

12. In a typewriting machine, the combination with a platen, of a carriage therefor, a main frame, a carriage-supporting frame 30 shiftable vertically on the main frame to various case-positions, means for moving the carriage in letter-feed direction, an escapement wheel mounted in the carriage-supporting frame, dogs for holding said escapement wheel, a rocker on which said dogs are mounted, said rocker mounted on said carriage-supporting frame, keys mounted in 35 said main frame, a universal bar operated

by said keys also mounted in said main frame, and connections between said universal bar and said dog rocker, said dog rocker being mounted about a vertical axis for horizontal movement and having a slot on one end through which the connections from the universal bar pass, said slot being 45 vertically disposed, whereby the dog rocker is controlled by the universal bar in all case-positions of the shift frame.

13. In a typewriting machine, a main frame, a platen frame shiftable between case-positions on the main frame, a platen mounted for letter-feed movement on the platen frame, means on the platen frame for driving the platen in letter-feed direction, type keys, and mechanism actuated thereby for 50 controlling the letter-feed drive of the platen, said key-actuated mechanism comprising a universal bar on the main frame, a rocker on the platen frame, an arm on the main frame connected to the rocker for vibrating the latter, a connection from the universal bar to said arm, a space-key, and a connection from the space-key to said arm, said arm having a pin-and-slot attachment to its space-key connection and a pin-and- 55 slot attachment to its universal bar connection, so that it may be operated by either connection independently of the other connection.
